UNITED STATES PATENT OFFICE.

ROBERT FRANZ WERK, OF NEW ORLEANS, LOUISIANA.

OIL-PRESS MAT.

SPECIFICATION forming part of Letters Patent No. 758,572, dated April 26, 1904.

Original application filed September 10, 1901, Serial No. 74,906. Divided and this application filed June 26, 1902. Serial No. 113,261. (No model.)

To all whom it may concern:

Be it known that I, ROBERT FRANZ WERK, a citizen of the United States, and a resident of New Orleans, in the parish of Orleans and 5 State of Louisiana, have invented a new and Improved Oil-Press Mat, of which the following is a full, clear, and exact description.

This invention relates to improvements in oil-press mats; and the subject-matter of the 10 present invention forms a division of a prior application for Letters Patent, filed by me on September 10, 1901, Serial No. 74,906.

In the manufacture of mats for oil-presses it is desirable to use animal hair, because such 15 a cloth or mat gives a cleaner oil than mats made of fibrous or other materials, and this is due to the fact that the oil when expressed from the material goes through the cloth or mat and is not forced out at the sides, where 20 there is nothing to prevent the loose meats from washing out with the oil. Mats made of animal hair are also superior, owing to the absence of sediment in the oil, which when present in the product requires to be eliminated by the process of filtration. Besides 25 this objection the presence of sediment serves to deteriorate the quality of the oil, to reduce the quantity of oil as the net result of the pressure and the filtration, and the settling- 30 tanks require frequent cleaning, and, finally, the residue with the sediment must be re-pressed or is entirely lost. If re-pressed, the residue produces a dark and inferior cake. The employment of hair mats overcomes these 35 practical objections and secures good drainage facilities for the passage and escape of the oil; but in my present invention I aim to produce a mat of superior durability, owing to the soft tread or cushion which is afforded 40 by soft weft-threads for the comparatively hard or coarse warp-threads in the body of the mat.

The present invention contemplates an oil-press mat or cloth consisting of warp-threads 45 and weft-threads, said warp-threads being composed of hard, stiff, coarse, and long animal hair and the weft-threads consisting of hard, stiff, coarse, and long animal hair mixed with soft, pliable, and long animal hair, the 50 said warp-threads being greatly in excess per

square inch of the weft-threads and in such close proximity to each other as to cover and protect the weft-threads, the warp-threads forming the selvage consisting of soft pliable hair.

The invention further consists of an oil-press mat or cloth composed of warp-threads and weft-threads made of hair, the warp-threads at the selvage being of soft hair and the threads in the body of the cloth or mat 60 having coarse strong hair.

Reference is to be had to the accompanying drawings, forming a part of this specification, in which similar characters of reference indicate corresponding parts in both the figures.

Figure 1 is a plan view of a portion of an oil-press cloth or mat constructed in accordance with the present invention, and Fig. 2 is a sectional elevation of the same in the plane of the dotted line 2 2 of Fig. 1.

The mat or cloth shown by the drawings consists of a plurality of longitudinal warp threads or strands A in the main or body portion thereof, a proper number of longitudinal warp-threads B at the selvage, and the weft-threads C, arranged to extend transversely across the body and selvage warp-threads and interlaced or interwoven therewith in a manner for the weft-threads to be entirely concealed and protected by the warp-threads.

Previous to weaving the warp and weft threads for the production of the fabric or mat the threads or strands are prepared by selecting the proper kind of hair and twisting the same together in a manner to produce the 85 threads or strands of proper size. The warp-threads in the body or main portion of the mat are made of animal hair which is long, hard, stiff, and coarse, and hair of this character having a thick and coarse filament is woven together to produce a strand of the proper length and thickness. The strands forming the weft-threads are made of two kinds of long animal hair—first, hair which is 90 hard, stiff, and coarse, and, second, hair which is soft and pliable.

It will be understood that in spinning the threads which are employed to produce the weft of the mat or cloth I select hair of medium texture. As hair of this character 100

is not readily obtainable, I prefer to mix long strands of hard hair with similar strands of soft hair, and thereby produce, in the technical phraseology of hair manufacturers, a product known as a "medium" grade of hair. The threads having been properly intertwined to produce the weft-strands, the latter are employed in the manufacture of the mat so as to be interwoven with the warp-strands in the body and the selvage of the fabric.

The warp-threads A in the body and the selvage warp-threads B are arranged alongside one another in parallel relation, while the weft-threads C extend across the warp-threads of the body and the selvage, so as to be covered thereby. The warp-threads in the body and the selvage of the cloth are from one to eight times in excess per square inch of the weft-threads in order to distribute the pressure of said warp-threads more evenly over the weft-threads. These weft-threads are from two to three times thicker than the warp-threads, and this is desirable because the weft-threads of increased thickness secure a more yielding and cushioning effect for the warp-threads.

It is obvious that the employment of warp-threads which are as thick as the weft-threads will serve to concentrate the pressure at the points where the warp and weft intersect each other; but by the use of an increased number of warp-threads a corresponding increase in the points of engagement of the two threads is secured, thereby reducing the pressure which the weft-threads are called upon to sustain.

The warp-threads B at the selvage are composed of long, soft, and pliable animal hair, the same being twisted together in order to secure strands which are more pliable than the warp-threads employed in the body of the mat or fabric.

The use of warp-threads in the body of the mat having the peculiar characteristics hereinbefore described secures increased strength and durability in that portion of the cloth or mat which is most exposed to the pressure of the seeds and the press-plates, and by weaving the cloth with the warps lying close together, so as to leave no space between adjacent warps, the seeds are prevented from passing between the warps and coming in contact with the weft-threads, thus reducing the shearing strain of the seeds upon the weft-threads and preventing the mat from splitting in a longitudinal direction. The employment of selvage threads or strands made of soft hair at the edges of the mat minimizes the tendency of the mat to give way at the selvage, especially when the body of the mat is made of warp-threads which are comparatively harsh and coarse.

The improved mat possesses all the desirable drainage properties which accrue from the use of animal hair, and at the same time it overcomes the objection so frequently encountered in breaking or shearing in the di-

rection of its length and at the body portion thereof, owing to the greater strain at the middle of the body when the press is closed.

Another advantage of the improved mat is that it may be folded longitudinally at any line either along the middle or side portions thereof. This folding of the mat can be accomplished without breaking or straining the same, owing to the longitudinal and parallel arrangement of the warp-strands and the employment of weft-strands, which are comparatively more pliable and fewer in number than the warp-strands.

Having thus fully described my invention, I claim as new and desire to secure by Letters Patent—

1. An oil-press cloth, consisting of warp-threads and weft-threads, the warp-threads being composed of hard, stiff, coarse and long animal hair, and the weft-threads being made of hard, stiff, coarse and long animal hair mixed with soft, pliable and long animal hair, said warp-threads being greatly in excess per square inch of the weft-threads, and in close proximity to each other so as to cover and protect said weft-threads, the warp-threads forming the selvage consisting of soft, pliable hair.

2. An oil-press mat or cloth consisting of warp-threads and weft-threads made of long animal hair, the warp-threads at the selvage being of soft hair, and the warp-threads in the body of the mat or cloth having coarse strong hair.

3. An oil-press cloth or mat consisting of hair warp-threads and hair weft-threads, the warp-threads in the body of the mat having hard, coarse and long animal hair, and the warp-threads at the selvage being of soft pliable hair, said weft-threads being thicker than the warp-threads.

4. An oil-press mat or cloth consisting of hair warp-threads and hair weft-threads, the warp-threads forming the selvage consisting of soft pliable hair.

5. An oil-press mat or cloth, consisting of hair warp-threads and hair weft-threads, the warp-threads greatly exceeding the weft-threads in number per square inch, and said warp-threads being of hair which is hard, coarse and strong except at the selvage, said selvage warp-threads having soft, pliable hair.

6. An oil-press mat consisting of warp-threads and weft-threads made of long animal hair, said weft-threads being composed of hair of medium grade, and the warp-threads forming the selvage being of soft pliable hair, said warp-threads exceeding the weft-threads in number per square inch.

In testimony whereof I have signed my name to this specification in the presence of two subscribing witnesses.

ROBERT FRANZ WERK.
